UNITED STATES PATENT OFFICE.

WILLIAM E. ELAM, OF WASHINGTON, DISTRICT OF COLUMBIA.

DRAWING APPARATUS.

Application filed August 13, 1923. Serial No. 656,993.

An object of this invention is to provide means whereby a triangle or analogous member to serve as a guide for a pencil or other marking implement may normally slide freely over the surface upon which marks are to be made, but which when pressure is applied to certain portions of its upper surface becomes non-slipping so long only as pressure continues on those portions.

10 In the accompanying drawings:—

Fig. 1 shows in plan view, a triangle provided with one form of my device,

Fig. 2 is a section on the line 2—2, Fig. 1,

Fig. 3 is a section similar to Fig. 2 showing a modified triangle.

In these views, G represents the body of a triangle or light plate.

In Figures 1 and 2 a resilient non-slipping member M normally lies wholly between the faces of the plate G and may be sprung downward into contact with the paper.

In Figure 3 thin strata of the plate have been removed over a suitable area as shown at N', N² leaving an integral thinner resilient portion O between, and normally spaced from, each of the plate faces. This thin part is resilient and its central portion may be pressed down upon the paper. In each form the lower face is preferably roughened e. g. by means of sand P, Fig. 3.

The plate may now be moved freely over the paper to exact position, and when so adjusted slight pressure of the fingers on the depressible area causes non-slipping engagement with the paper, but only as long as 35 pressure continues. This normal easy slipping is highly important under various conditions, e. g. when two plates, or triangles, are in marginal contact and are to be slipped alternately.

40 What I claim is:—

1. A draftsman's plane marking guide plate having an integral thinner resilient portion between and normally spaced from each of the plate faces and adapted for non-slipping engagement with the drawing surface while pressed against that surface.

45 2. In apparatus of the class described, a guide plate adapted to rest upon a surface upon which a line is to be drawn and provided with a thinner resilient non-slipping portion secured to the plate at the margins of said non-slipping portion and normally lying wholly between the faces of said plate.

50 55 In testimony whereof I hereunto affix my signature.

W. E. ELAM.
